US0D1063364S

(12) **United States Design Patent** (10) **Patent No.:** **US D1,063,364 S**
(45) **Date of Patent:** **** Feb. 25, 2025**

(54) **BACKPACK**

(71) Applicant: **Dongguan Gaoyi Electronic Technology Co., Ltd**, Dongguan (CN)

(72) Inventor: **Jianbin Long**, Dongguan (CN)

(73) Assignee: **Dongguan Gaoyi Electronic Technology Co., Ltd**, Dongguan (CN)

(**) Term: **15 Years**

(21) Appl. No.: **29/868,903**

(22) Filed: **Dec. 15, 2022**

(51) LOC (15) Cl. **03-01**

(52) U.S. Cl.

USPC **D3/216; D3/217**

(58) **Field of Classification Search**

USPC D3/216–217, 225, 226, 230–232, D3/252–254, 262, 285–289, 303,

D3/321–328; D9/703–707, 710

CPC A45F 3/02; A45F 3/04; A45F 3/08; A45F 3/10; A45F 3/14; A45F 3/042; A45F 3/047; A45F 2200/00; A45F 4/02

(57) **CLAIM**

The ornamental design for the backpack as shown and described.

DESCRIPTION

FIG. 1 is a top, front, right perspective view of a backpack of my new design;

FIG. 2 is a bottom, rear, left side perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a perspective view thereof, illustrated in an open configuration.

The broken lines in the figures depict portions of the backpack that form no part of the claimed design. The zipper stitching shown in the figures also forms no part of the claimed design.

1 Claim, 9 Drawing Sheets
